UNITED STATES PATENT OFFICE.

WALTER E. MURRAY, OF FORT DODGE, IOWA, ASSIGNOR, BY MESNE ASSIGNMENTS,
TO PEOPLES INVESTMENT COMPANY, A CORPORATION OF SOUTH DAKOTA.

AUXILIARY SAFE AND VAULT LOCK.

Application filed June 8, 1921. Serial No. 475,977.

To all whom it may concern:

Be it known that I, WALTER E. MURRAY, a citizen of the United States, and a resident of Fort Dodge, in the county of Webster and State of Iowa, have invented 5 certain new and useful Improvements in Auxiliary Safe and Vault Locks, of which the following is a specification.

My invention relates to auxiliary safe 10 and vault locking mechanism, for use in preventing unauthorized opening of safes and vaults by destruction of the usual combination-controlled locking means. It is the object of my invention to provide a simple 15 and inexpensive auxiliary locking means, which may be readily applied to the locking mechanism of safes and vaults, and which is automatically operable to prevent opening of the safe or vault door should the 20 usual combination-lock be destroyed or dislocated by mechanical force, or should an attempt be made to cut through the door by means of an electric arc, oxy-acetylene torch, or other means involving the application 25 of heat.

In the accompanying drawings Fig. 1 is a side view of my auxiliary locking device, Fig. 2 is a plan view of the same, Fig. 3 is a transverse section thereof on the line 3—3 30 of Fig. 1, Fig. 4 is a view of the inner side of a vault door equipped with the auxiliary lock, and Fig. 5 is a detail showing the connection of the latch-holding means with the combination-lock-casing.

The illustrated embodiment of my invention is particularly adapted for use upon a vault door of the type shown in Fig. 4, wherein the door-plate 7 has near the edges thereof inwardly extending flanges 8 35 through which the bolts 9 pass slidably, the horizontal bolts being connected with each other by a vertical bar 10 having the usual connection with a handle by which the bolts are moved to locked and unlocked positions, and there being the usual combination-lock arranged in a casing 11 and operable to prevent movement of the bolts when locked.

My auxiliary lock comprises a bar or 50 frame-piece 12 which is disposed in a horizontal position adjoining the inner side of the door-plate 7, with one end of the bar abutting the flange 8 and fixedly secured thereto by a single cap-screw 13. At the 55 opposite or inner end of the frame-piece

or bar 12 there is secured a vertically extending plate 14, and to the upper end of said plate is secured the end of a tubular spring-casing 15. The latter first extends from the plate 14 horizontally above the frame-piece 12, and then curves downwardly to the upper side thereof, entering an opening therein and being secured by a transverse screw 16. The lower side of the curved portion of the tube, and of the adjacent end of the horizontal portion thereof, are slotted to receive a movable finger 17 forming the terminal portion of a plate 18 which is secured to the tumbler-block 19 by means of screws 20. A small plunger 21 fit slidably within the tube 15 and is pressed against the finger 17 by means of the spring 22. The tumbler-block 19 is pivoted upon a screw 23 at the side of the frame-piece 12, and is movable about said pivot-screw from the vertical position shown in Fig. 1 to a horizontal position indicated by dotted lines in the same figure. The plate 18 has an offset portion extending in over the upper side of the frame-piece 12, and in the last-named position of the tumbler-block said offset portion of the plate rests upon the upper side of the frame-piece, forming a stop to prevent movement of the tumbler-block beyond the horizontal position. The pressure of the spring 22 against the plunger 21, and of the latter upon the finger 17, constantly tends to move the tumbler-block to the horizontal position.

For retaining the tumbler-block in the vertical position there is provided upon the plate 18 a loop 24 which is adapted to be engaged by the latch-hook 25. The shank of the latch-hook extends slidably through a vertical opening in the frame-piece 12 near the end-plate 14 thereon. A tubular casing 26 encloses the upper portion of the shank, and a coil spring 27 is arranged around the shank within the casing, the upper end of the spring engaging a collar 28 on the shank and thus tending to lift the latch-hook out of engagement with the loop 24.

The auxiliary lock is so disposed that when the tumbler-block is in its horizontal 105 position the end thereof will engage the edge of the vertical bar 10 and prevent the movement thereof necessary to withdraw the bolts 9 to the unlocked position, and when the tumbler-block is in its vertical po- 110

sition it will not interfere with the usual movements of the bolts and bar 10.

Normally the tumbler-block is retained in the raised or inactive position by engaging the latch-hook with the loop 24, and holding the latch-hook in said engaged position by means of a tension-member 29 which is connected therewith at its end and extends to a hook 30 arranged on the lock-casing 11, 10 as shown in Figs. 4 and 5. A portion of the tension-member is formed by one or more fusible links 31, comprising parts which are normally united by a material fusible at a relatively low temperature, whereby 15 by the application of any excessive or abnormal heat will melt said connecting material and permit the separation of the link-parts.

It will be readily seen that by the arrangement 20 of the auxiliary lock in the manner shown and described, it will not normally interfere with the usual operation of the regular locking mechanism for the door. Should any attempt be made, however, to 25 open the door by destruction or dislocation of the combination-lock, the displacement of the casing 11 will result in freeing the tension-member from the hook 30, and thus release the latch-hook to permit movement of 30 the tumbler-block to its operative, horizontal or locking position. Similarly, an attempt to cut through the door by means of an electric arc, or by an oxy-acetylene torch, will result in the breaking of the tension-member at the fusible links, and release the 35 latch-hook. In fact, almost any attempt to open the door by force, or otherwise than by the normal operation of the combination lock, will result in the breaking or disconnection 40 of the tension-member and thus cause the operation of the auxiliary lock, thereby offering an unexpected obstacle to the opening of the door, sufficient in most cases to defeat the attempt.

45 Now, having described my invention, what I claim and desire to secure by Letters Patent is:

1. The combination with safe and vault locking means including locking-bolts and 50 a main locking mechanism therefor, of an auxiliary lock having a support, a tumbler-block pivoted thereon, a tubular member carried by said support and having a longitudinal slot, an expansive spring in said tubu-

lar member, said tumbler block being 55 formed with a portion projecting through said slot and engaged by said spring, said spring tending to move said tumbler-block to active position, and means for holding said tumbler-block in an inactive position, 60 said holding means being releasable by abnormal movement of the main locking means.

2. The combination with safe and vault locking mechanism comprising locking-bolts and main locking means therefor, of an auxiliary lock having a tumbler-block biased to a locking position for preventing movement of the locking-bolts, a latch for holding said tumbler-block at an inactive position, means 70 tending to disengage said latch from the tumbler block, and a tension member for retaining said latch in engagement with the tumbler-block, said tension member being 75 detachably connected with the main locking means and releasable therefrom by abnormal movement thereof.

3. An auxiliary lock for safe and vault doors, comprising a frame-piece adapted for attachment to the bolt-frame of the door, a 80 tumbler-block pivoted on said frame-piece and movable from an inactive position to a bolt-intercepting position, a spring tending to move the tumbler-block to the last-named position, a latch for holding the tumbler-block at an inactive position, a spring tending to move the latch to release the tumbler-block, a tension member connected with 85 said latch and normally holding the same in engaged position, and fusible links forming 90 a part of said tension member whereby the same will be broken and the tumbler-block released upon exposure of the parts to abnormal heat.

4. The combination with main locking 95 mechanism for safes and vaults, including a combination-lock casing, of auxiliary locking means, a member normally holding said auxiliary locking means in an inactive position, and a hooked member in engagement 100 with the combination-lock casing, said holding member being detachably connected with said hooked member so as to be disconnected and freed therefrom by abnormal movement of said casing, a portion of said holding member being formed of materials fusible upon exposure to abnormal heat.

WALTER E. MURRAY.
